Company, East Pittsburgh, Pa., a corporation
of Pennsylvania

Application December 1, 1937, Serial No. 177,475

25 Claims. (Cl. 175—294)

My present invention is an improvement over the pilot protective systems which are described and claimed in a copending application Serial No. 110,660, filed November 13, 1936, by Edwin L. Harder, William A. Lewis and myself.

The principal object of my invention is to provide an improved ground-preference system whereby preference may be given to the control of carrier-current, or, in general, current in a pilot-channel, in response to ground-faults (or phase-faults if desirable) without resort to a special ground-preference relay in addition to the usual ground and phase-fault-responsive relays which are otherwise required by the protective system.

A further object of my invention is to provide an intermittent-carrier relaying system having a normally non-tripping receiver-relay with means tending to move the receiver-relay to its tripping position in response to detector-supervised directional elements.

With the foregoing and other objects in view, my invention consists in the circuits, apparatus, systems, combinations and methods hereinafter described and claimed, and illustrated in the accompanying drawings wherein:

Figure 1 is a simplified diagrammatic view of circuits and apparatus embodying my invention in one preferred form of embodiment, features which are unnecessary to an understanding of my invention being omitted for the sake of clearness;

Fig. 2 is a so-called "across the line" diagram of the direct-current connections of the same relaying system as that shown in Fig. 1, except that the CSP and CSG relay-coils are connected to the negative terminal (—) through the auxiliary contact 9 of the circuit-breaker, which is a preferred connection; and

Fig. 3 is a fragmentary view similar to Fig. 2, illustrating a modification.

As shown in Fig. 1, my invention is illustrated as being applied to the protection of one end of a protected line-section 4 of a three-phase transmission line, only one end of the protected section being illustrated as the other end may be similar thereto, in its relaying equipment. The protected line-section 4 is energized from a power transformer bank 5, the secondary side of which is grounded as indicated at 6, and the primary side of which is energized by a synchronous dynamo-electric machine or generator G. It will be understood that other circuits or lines, similar to the line-section 4, and other loads or sources, will in general be connected to the illustrated end of the line-section, the simplest possible con-

nections being illustrated for the sake of clearness.

Each end of the protected line-section 4 is provided with a line-sectionalizing circuit-interrupter 7 which may be an oil circuit-breaker provided with a trip-coil 8 and having auxiliary contacts 9 which are closed when the circuit-interrupter or breaker is closed.

My protective system, for controlling the tripping of the circuit breaker 7, utilizes both line-frequency relays and a carrier-current system or other pilot-channel system for transmitting and responding to relaying signals to and from the other end of the protected line-section.

The line-frequency relays are illustrated as 15 being energized from a group of line-current transformers 11 and potential transformers 12, and are arranged essentially in four panels 13, 14, 15 and 16, the first three of which are phase-to-phase relays and the last of which is composed of 20 ground protective relays, and in addition, I utilize certain auxiliary relaying equipment which will be subsequently described.

The carrier-current equipment for the end of the line-section illustrated in Fig. 1 comprises 25 a carrier-current transmitter 18 and a carrier-current receiver-relay 19, both tuned to the same high or carrier-current frequency and both coupled to the protected line-section by means of a coupling transformer 21 and a coupling capacitor 22. In addition, it is necessary to provide a resonant carrier-frequency choke coil or wave-trap 23 in the line-wire to which the carrier is coupled, as indicated; and it is necessary to have a receiver-relay, marked RR, which responds to the receipt of suitable carrier-currents or signals.

The phase-fault line-frequency relaying equipments 13, 14 and 15 are all alike except that they are connected to be responsive to different phases 40 of the transmission line, as indicated by the distinguishing subscripts A, B and C in the symbols designating the various relay elements, so that a description of the relay elements comprising the group 13 will suffice also for the groups 14 and 15. 45

The relay panel 13 utilizes three so-called "instantaneous" impedance relays which are set to respond to different distances or zones known as zones 1, 2 and 3, as indicated by the symbols Z1A, Z2A and Z3A, the letter "A" indicating 50 the phase in which the relay is connected. The balance-point of the first impedance element Z1A is necessarily within the length of the protected line-section, and is as close to the far end of the same as it is possible to make it without 55

running the risk of a response to any fault-conditions which are further than the far end of the protected line-section. The second impedance element Z2A has its balance-point somewhere beyond the far end of the protected line-section and usually, but not necessarily, in the next section beyond. The third impedance element Z3A is still more sensitive, being set to respond to faults which are still more remote. Each of these impedance elements is provided with a current-responsive actuating coil 24 tending to actuate the relay, and a voltage-responsive restraining coil 25 tending to restrain the operation of the relay.

15 The impedance relays Z1A and Z2A are shown as having their current coils 24 energized by the delta current, for the accurate measurement of impedance, as set forth in Goldsborough Patent No. 1,877,454, granted September 13, 1932, and 20 in Lewis and Evans Patent No. 2,044,174, granted June 16, 1936. This delta current is in reality 25 the difference between the line-currents in two of the phases of the protected section 4, said difference being obtained by means of auxiliary current-transformers 28.

In the illustrated embodiment of my invention, the impedance relay Z3A has its current coil 24 energized in response to the line-current in phase A, as distinguished from being responsive to a 30 delta current. This is advantageous when certain kinds of out-of-step protection are added to the protective circuits, and it has the added advantage of relieving the burden on the auxiliary current-transformers 28.

35 The voltage coils 25 of all three of the impedance relays Z1A, Z2A and Z3A are energized by the phase-to-phase line-voltages, in the same phases to which the current coils of relays Z1A and Z2A respond, the voltage-coil potential being 40 supplied by the potential transformer 12.

45 The relay panel 13 also comprises a so-called "instantaneous" directional element DA which is designated schematically as a wattmeter indicated by the letter W; a timing element which is designated schematically as a motor M, a movable arm 32 of which makes the successive contacts T2A and T3A for cooperating with the second and third-zone impedance elements Z2A and Z3A respectively; an auxiliary relay or contactor-switch CSA; and also the previously mentioned auxiliary relay A for use in out-of-synchronization control.

50 The current-coil of the directional element DA is necessarily energized in response to the same current which actuates the first and second-zone 55 impedance elements Z1A and Z2A, this being necessary in order to prevent faulty operation of my relaying equipment.

50 The timer motor M is energized by any suitable means such as an auxiliary current-transformer 33 which is connected in series with any of the current coils 24 of this panel 13. In the illustrated form of embodiment, the current-transformer 33 is normally short-circuited by means 65 of back-contacts 35 on the directional element DA, although this feature is usually not needed. The timer motor M is connected to the current-transformer 33 by means of one of two sets of front or "make" contacts 36 of the auxiliary relay CSA, and this feature, or its equivalent, is necessary. Thus the timing motor M is energized 70 only when the auxiliary relay CSA is energized and when, at the same time, the directional element DA is actuated. The directional element 75 is connected so as to respond only when there is

a line-frequency current-flow in an "internal" direction, that is, from the transformer 5 into the protected line-section 4.

The ground-relay panel 16 comprises two so-called "instantaneous" ground-overcurrent relays IOH and IOL which are energized from the neutral of the line-current transformers 11. These relays are of different sensitivities, the first one being a high-current relay, as indicated by the letter H, and the second one being a more 10 sensitive, low-current relay, as indicated by the letter L.

The ground-relay panel 16 also comprises a so-called "instantaneous" ground directional element DO which is illustrated as being a wattmeter designated by the letter W, the current coil of this wattmetrical element being energized from the residual line-current in series with the coils IOH and IOL, and the voltage coil of said wattmetrical element being energized by residual 20 voltage or by residual current obtained by a current transformer 38 in the ground-connection 6 of the power-transformer bank 5. The connections for the directional element DO are such that this relay element responds only for an 25 "internal" direction, that is, when the direction of the ground current is such as to indicate that the ground fault is on the same side of the power transformer 5 as the protected line-section 4.

The carrier-current transmitter 18 is illustrated 30 as being of a type having a master-oscillator tube 39 which is shown as being a triode comprising a cathode 40, a grid 41, and a plate or anode 42. The oscillator-tube 39 is of such a type that the oscillations are blocked when a predetermined 35 negative bias is applied to the grid 41 through the grid-control circuit 43, the cathode 40 being permanently connected to the positive station-battery terminal (+).

40 My receiver 19 is illustrated as comprising, 45 inter alia, a receiver tube 44, having a cathode 45 which is connected to the negative terminal B—of the "B" battery, and having a plate 46 which is connected to the plate-circuit or output-circuit 48 of the receiver.

45 My receiver-relay R is of special construction, an improved form of which is described and claimed in an application of B. E. Lenehan and A. W. Rogers, Serial No. 114,964, filed December 9, 1936. Some of the most essential features of the 50 receiver-relay are indicated in Fig. 1 of my drawings, from which it will be seen that the relay is of the polarized type, having a permanent magnet 50 at its base. The relay has a movable armature 51 of soft iron, which is pivoted by means of a spring-portion 52 which is connected to a central core 53 extending from the mid-point of the permanent magnet 50. Two special pole-pieces 54 and 55 are provided for carrying the 55 magnetic flux from the terminals of the permanent magnet 50 to the front and back sides, respectively, of the armature 51, the pole-pieces 54 and 55 being preferably slightly separated, magnetically, from the ends of the permanent magnet 50, by means of shims or spacers 56 of 60 brass or other non-magnetic material.

65 The central core 53 of the receiver-relay RR is provided with two coils, namely a trip coil marked RRT and a blocking or holding coil marked RRH. The trip coil RRT is adapted to 70 be energized in such direction as to produce an operating force tending to move the armature 51 away from a back-stop 58, so as to make two sets of front-contacts 59 and 60. The blocking coil RRH is more powerful than the tripping coil 75

5 RRT and is designed to be energized in such direction that it will tend to hold the armature back against its back-stop 58. In addition to these two forces, the receiver relay also has a continuously operative biasing torque which is provided, partly by the spring pivotal connection 52, and partly by an off-center mounting of the movable armature 51 between the faces of the two pole-pieces 54 and 55, so that the armature is normally 10 a little bit nearer to the back pole-piece 55, thereby developing a magnetic force tending to hold the armature 51 against its back-stop 58 as a result of the magnetism of the permanent magnet 50.

15 The operating connections of the various parts of my system are shown in both Figs. 1 and 2, and may perhaps best be followed with reference to Fig. 2, although the connections may be traced in either figure. The station battery is indicated only in Fig. 1, near the circuit-breaker 7, where it is designated by the numeral 61. It is provided with a positive terminal (+) and a negative terminal (-), and it is indicated in Fig. 2 only by means of its two terminals (+) and (-) respectively.

20 Starting at the top of Fig. 2, it will be noted that the directional element DA is provided with a make-contact which establishes a partial circuit from the positive terminal (+) to a phase-directional bus 62A. Connected to the phase-directional bus 62A is one terminal of a make-contact carried by the first impedance element Z1A, the other terminal of which is connected to a tripping bus 63T, which is connected to the 25 trip-coil 8 of the circuit breaker, and thence, through the auxiliary circuit-breaker contact 9 to the negative bus (-).

30 Before proceeding further with the next contacts shown at the top of Fig. 2, it is necessary to refer further down in the figure, where it is seen that the operating coil of the auxiliary relay CSA is connected between a so-called phase-fault carrier-starting bus 64 and the negative terminal (-), through a resistor 65, also designated RA in Fig. 2 in order to distinguish this resistor from the corresponding resistors RB and RC in the other phases.

35 The phase-fault carrier-starting bus 64 is energized from the positive terminal (+) by means of the closure of normally open or "make" contacts of any one of the three third-zone phase-fault impedance-elements Z3A, Z3B or Z3C. The operating coil of the relay CSA is normally short-circuited by a back-contact of the third-zone impedance element Z3A. Said operating coil of the relay CSA is connected, on one side, through the resistor RA, to the negative bus (-), and is connected, on the other side, to the phase-fault carrier-control bus 64. The phase-fault carrier-starting bus 64 is energized by the response of any one of the three third-zone impedance-elements Z3A, Z3B or Z3C, this energization of the bus being promptly and directly effected by the closure of the front contact of the actuated element Z3A, Z3B or Z3C, and this front contact, which initially energizes said bus 64, will be immediately bypassed by a make-contact of the corresponding auxiliary contactor-switch or relay CSA, CSB or CSC as the case may be. The operating coil of the CSA relay (for example) is normally shunted by a closed back-contact of the Z3A relay, so that this CSA relay cannot operate unless its particular associated Z3A relay responds to faults on the transmission system.

40 Referring, now, to Fig. 1 it will be seen that

45 the CSA relay, through its make-contacts 36, controls the energization of the timer motor M which is associated with the timer contacts T2A and T3A. The starting of the timer motor M is dependent, also, upon a response of the "internal" 5 directional element DA, which response is necessary in order to remove the short-circuit at the back contacts 35 of the directional element. It will be seen, therefore, that as soon as the third impedance element Z3A and the directional element 10 DA respond, the auxiliary relay CSA is energized, starting the timer motor M which in predetermined times first closes its timer contact T2A, and later on, its timer contact T3A.

15 Referring again to the top portion of the across-the-line diagram in Fig. 2, it will be seen that there is a second energizing circuit for the tripping bus 63T from the phase-directional bus 62A through the front contact of the second impedance element Z2A and thence through the timer contact T2A. The purpose of this energizing circuit is to provide for what is known as sequential tripping in the event that the carrier-current system is not utilized or is out of operation; that is, if there is a fault on the protected line-section 20 very close to the far end of the line-section, so that the first impedance element Z1A will not respond, the fault will not be cleared at the relaying station under consideration until the elapse of a certain time determined by the T2A contact, 25 30 which will provide ample time for the fault to be cleared by the instantaneous tripping element Z1A at the beginning of the next adjacent line-section (not shown) if it should be that the fault were just beyond the end of the line-section 4 35 rather than just before the end of the line-section 4. Meanwhile the fault is instantaneously cleared at the far end of the protected line-section by the Z1A tripping contact at that end, thereby resulting in the sequential tripping of 40 the fault, first at the end which is closest to the fault, and second at the end where the fault is so far away that the first-zone impedance relay element cannot discriminate between faults lying in the very extreme end of the line-section and 45 faults occurring in the beginning of the next adjacent line-section beyond the section which is being protected.

50 The partial tripping circuits which may be traced through the directional and impedance contacts DA and Z2A in each of the three single-phase, phase-fault-responsive relaying elements, that is, including the partial tripping circuits provided by the make contacts of DB-Z2B and DC-Z2C, are bussed together by means of 55 a phase-fault bus 69 which is thus energized whenever there is a phase-to-phase fault across any two of the line conductors of the line-section 4, close enough to energize the second impedance element of the corresponding line-frequency phase-relays, if, at the same time, the fault-current is in the "internal" direction, so as to pick up the corresponding directional element DA, DB or DC in that particular phase.

60 As is previously known in carrier-current protective systems, and as shown in Figs. 1 and 2, I utilize a make-contact 59 of my receiver-relay RR to directly connect the phase-fault bus 69 with the tripping bus 63T under the control of carrier, so that the carrier-current protection 70 may be utilized to discriminate between the faults which are just beyond the end of the protected line-section and faults which are just within the end of the protected line-section, so as to eliminate the timing element provided by the T2 75

timing contacts in the three phase-relaying panels.

Fig. 2 also shows a back-up energizing circuit for the tripping bus 63T, through the make-contacts of the third-zone impedance element Z3A and the longtime contacts T3A which eventually complete a circuit directly from the phase-directional bus 62A to the tripping bus 63T, thus providing backup protection in the event that the fault is not properly cleared by relays at other stations which are closer to the fault, before the elapse of the time-setting of the T3A contacts.

It will be understood that the foregoing description, which is mainly directed to the line-frequency phase-fault relay-panel 13, is equally applicable to the other two phase-panels 14 and 15, with a change of subscript to designate the B or C phases rather than the A phase.

The particular system shown in the drawings includes a novel form of ground-fault protection which is the subject-matter of an application of Edwin L. Harder, Serial No. 177,560, filed concurrently herewith. This ground-protection system comprises separate ground-fault tripping and carrier-starting relays IOH and IOL, respectively, the latter being the more sensitive, that is, picking up at a lower value of the neutral or residual current. For simplicity of illustration, I have shown only the pilot-supervised ground-fault tripping-circuit including the "make" contacts of the ground directional relay DO and the high-current ground relay IOH, which together energize an intermediate bus 72, which is in turn connected, by the "make" contacts 60 of the receiver-relay RR, directly to the tripping bus 63T which is connected to the trip coil 8.

The particular system which I have illustrated also utilizes a novel form of grid-bias control which is more specifically claimed in the companion Harder application for starting the carrier-current transmitter 18 in such a manner that the fault-detectors for starting the carrier-current transmission are separate from the fault-detectors which cause tripping under carrier-current control, that is, separate from the fault-detectors which have tripping contacts in series with the receiver-relay contacts 59 and 60; and these carrier-starting fault-detectors are set for a lower operating value than the aforesaid carrier-supervised tripping-circuit fault-detectors, for both phase and ground faults. Thus, the phase-fault carrier-starting bus 64 is energized by a response of any one of the third-zone impedance relays Z3A, Z3B or Z3C, which are more sensitive than the corresponding carrier-supervised trip-circuit second-zone impedance relays Z2A, Z2B and Z2C which energize the phase-fault bus 69 in the tripping circuit. In like manner, the carrier-starting low-current ground-fault relay IOL is more sensitive than the carrier-supervised trip-circuit high-current ground-fault relay IOH which energizes the intermediate bus 72 in the tripping circuit. This precaution is for the purpose of insuring that the carrier-starting element or relay at one end of the protected line-section always functions at the same time as, or prior to, the operation of the trip-circuit fault-responding element at the other end of the line-section. This precautionary measure must be provided for ground faults as well as for phase faults.

It is frequently necessary to provide preferential control, which is vested in either the ground-fault relays or the phase-fault relays

(usually the ground-fault relays), in order that the starting and stopping of the carrier signal will be controlled by the preferred relays, regardless of the operation of the other relays. Ground-preference is the most frequently desired, in order to prevent possible incorrect indications of the phase-current directional elements as a result of load-currents flowing in a direction opposite to the ground-fault currents on certain types of transmission systems. On the other hand, in some cases it may be desirable to give the phase-relays preference over the ground-relays, or to have no preference at all. Usually, however, ground-preference is desired, in order to properly relay in response to single-phase ground-faults, notwithstanding the fact that this ground preference would block the carrier-controlling function of the phase-relays in case of a double line-to-ground fault, or simultaneous ground-faults at two different locations in a protected line section.

According to my invention, I provide this preferential action, of whichever kind is desired, usually ground-preference, in an improved manner which does not necessitate the utilization of a separate ground-preference relay for this purpose.

Thus, referring to the lower portion of Fig. 2, it will be noted that the transmitter-grid 41 is controlled by means of three serially connected resistors R1, R2 and R3, the resistor R1 being closest to the grid. The third resistor R3 is normally connected to the negative bus (-1) through the phase-fault carrier-control bus 64 and the three parallel-connected resistors RA, RB and RC, thus making the grid negative.

The transmitter grid 41 is thus negatively biased, so as to block transmission, in the normal state of affairs, that is, when there is no fault on the transmission line.

In the event of a phase-fault on the transmission system, one or more of the sensitive phase-fault impedance relays Z3A, Z3B or Z3C will pick up and make a connection between the positive bus (+) and the phase-fault carrier-starting bus 64, thus making the grid-control resistor R3 positive instead of negative, initiating carrier-current transmission by the transmitter 18. If this phase-fault is accompanied by fault-current direction into the protected line-section at the illustrated end of said line-section, and if the fault is within the reach of the second-zone impedance-elements Z2A, Z2B and Z2C, the corresponding second-zone impedance element or elements Z2A, Z2B or Z2C will pick up, as will also the corresponding phase-directional element or elements DA, DB or DC, thus energizing the phase-fault bus 69, which in turn energizes the operating coil of an auxiliary phase-fault contactor-switch or relay CSP, the other terminal of which is connected to the negative bus (-) through the auxiliary contact 9 of the circuit breaker. This CSP relay picks up quickly and closes its "make" contacts, one of which is connected between the negative bus (-) and the junction 78 between the resistors R2 and R3. This causes the resistor R2 to become negative again, thereby applying a negative bias to the transmitter grid 41 and stopping the transmission of carrier-current.

If a ground-fault occurs on the transmission system, the sensitive carrier-starting ground-fault relay IOL will make a connection between the positive bus (+) and the junction 80 between the resistors R1 and R2, thus making the resistor

R1 positive, regardless of the condition of the phase-fault control-points 64 and 78, thus providing ground-fault preference. When the point 80 is made positive, the transmitter grid 41 is positive and carrier-current is transmitted. If the ground-fault is of sufficient intensity to pick up the less sensitive ground-fault relay IOH, which may be regarded as corresponding in scope to the second-zone phase-fault impedance elements Z2A, Z2B and Z2C, and if, at the same time, the direction of the ground-current is such as to indicate that the ground-current is flowing away from the relaying terminal under consideration and into the protected line-section, the ground directional element DO will also pick up, thereby energizing the intermediate bus 72, connecting said bus to the positive terminal (+). I have provided a ground-fault contactor-switch or relay CSG, the operating coil of which is connected between this intermediate bus 72 and the auxiliary breaker-switch or contact 91, which is connected to the negative bus (-). This CSG relay immediately picks up and closes its "make" contacts, one of which is connected between the grid-terminal 43 of the transmitter 18 and the negative bus (-), thus making the grid 41 negative again, and blocking the transmission of carrier, regardless of all other controls on the carrier-current transmitter 18, thus providing again for ground-preference.

As shown at the bottom of Fig. 2, the two coils RRH and RRT of the receiver-relay RR are controlled as follows. The holding or blocking coil RRH is connected between the positive B-battery terminal B+ and the plate circuit 48 of the receiver 19, so that this coil RRH is energized whenever the receiver 19 receives a sufficient amount of carrier-current energy from the transmitter 18 at either end of the protected line-section. The tripping coil RRT of the receiver-relay RR is connected, on one side, to the positive bus (+), and on the other side it may be connected to the negative bus (-) by one of the make-contacts of either of the CSP or CSG relays, which respond to "internal" phase-faults and "internal" ground-faults, respectively. In this way, the tripping coil RRT of the receiver-relay is not energized until both an insensitive fault-detector response Z2A, Z2B, Z2C or IOH, and a directional response DA, DB, DC or DO, are obtained, which takes longer than a sensitive non-directional fault response Z3 or IOL. The sensitive fault-detectors Z2 and IOH require more current, to operate them, and thus are not only slower than Z3 and IOL, for any given fault-current, but also sometimes may not operate at all for fault-currents which are just barely sufficient to operate Z3 or IOL. The energization of the tripping coil RRT is still further delayed by the slight operating-time required by the auxiliary relay CSP or CSG, as the case may be. Thus an ample factor of safety is provided, to make sure that the holding coils RRH shall be energized, at both ends of the protected line-section, before either tripping coil RRT can possibly be energized.

It is believed that the operation of my carrier-current or pilot-channel relaying equipment will be obvious from the drawing and from the foregoing description. The receiver relay RR is normally biased to its illustrated position, with its movable element against the back-stop 58, and with its front-contacts 59 and 60 open. If a fault occurs anywhere within the protected line-section, the first thing that happens will be for the sensitive fault-detector Z3 or IOL, as the

case may be, to operate, changing the transmitter grid 41 from a negative bias to a positive potential, and starting the transmission of carrier. This immediately puts carrier on the protected line-section and operates the receiver-relay holding coils RRH at both ends of the line-section, thus insuring that the receiver-relays RR shall remain in their normal non-tripping positions, regardless of whether their operating or tripping coils RRT are energized or not.

If there is a fault within the reach of the second-zone impedance element Z2 or the insensitive ground element IOH, accompanied, in either case, by an "internal" direction, or direction into the protected line-section, the auxiliary relay 15 CSP or CSG at the terminal where this internal direction occurs will be operated, closing its make contacts CSP or CSG and energizing the operating or tripping coil RRT of the receiver relay RR at that station. At the same time, the same 20 relay CSP or CSG, as the day may be, will change the transmitter grid-bias so as to block transmission of carrier-current at that station. Unless, however, there is a similar "internal" direction registered at the other end or ends of the 25 protected line-section, carrier-current will not be removed from the line-section at said end or ends, so that the receiver-relay holding-coils RRH will remain energized at both or all ends of the line-section, thus preventing the closure 30 of either one of the receiver-relay tripping-contacts 59 or 60. If the direction is "internal" at both or all ends, carrier will be altogether removed from the line-section, the receiver-relay holding-coils RRH will be deenergized, and the 35 receiver-relay tripping-coils RRT will actuate the respective receiver-relays RR to their tripping positions, closing their contacts 59 and 60 in the trip-circuits.

A modified form of the carrier-transmitter 40 control is illustrated in Fig. 3, which is intended to replace the bottom portion of the Fig. 2 diagram, below the make-contact of the CSG relay. In this modification, which, in some respects may be preferred to the one which is shown in 45 Figs. 1 and 2, I utilize back-contacts on the sensitive fault-detectors for initiating the carrier-current transmission by changing the grid-bias from negative to positive, thereby starting the 2 modification in which front- or make-contacts 50 were utilized for this purpose. This quick starting of the carrier is, or may be, frequently desirable in some systems in which there are conditions in which it is difficult to coordinate the 55 speeds of operation or the pick-up points of the relays at the two ends of the protected line-section, to make certain that carrier shall be transmitted, from one end, thus blocking tripping, before the tripping-circuit can be set up through 60 the receiver-relay tripping contacts 59 or 60 at the other end.

In the relaying system shown in Fig. 3, the sensitive ground-fault detector IOL is provided with a back-contact 91 instead of having a front- 65 contact as in Fig. 2; and the sensitive phase-fault detectors Z3A, Z3B and Z3C have additional back-contacts 92, in addition to the contacts which are required in the embodiment of my invention which is shown in Figs. 1 and 2. In Fig. 70 3, the phase-fault bus 64 is not utilized in the control of the transmitter, and the resistors R1, R2 and R3 are replaced by a single resistor R.

The grid-circuit of the transmitter-tube 39 starts, as before, with the grid lead 43; and, as 75

before, the first contact which is made to this grid-circuit, at a point close to the grid 41, that is, in a connection to the grid-lead 43, is a connection through the make-contact of the CSG 5 relay, which makes certain, regardless of any other controls, that the grid shall be connected to the negative bus (—) whenever the CSG relay picks up in response to ground-faults with an internal direction.

10 From this point on, however, the connections are different from those in Fig. 2. The resistor R, in Fig. 3, is connected between the grid-lead 43 and the positive bus (+), but the grid-lead is normally held to a negative potential by being connected through the four fault-detector back-contacts 91 and 92, all connected in series between the grid-lead 43 and the negative bus (—). The three phase-fault-detector back-contacts 92 of the impedance elements Z3A, Z3B 15 and Z3C are shunted by the CSP make-contact which responds to a phase-fault condition accompanied by an internal direction of current-flow. This CSP make-contact is thus in series with the ground-detector contact 91, so that when the ground-detector contact 91 is open, in response to a ground-fault, a subsequent closure of the CSP make-contact will not have any effect at all upon the potential of the transmitter-grid 41.

20 The Fig. 3 control operates as follows. Normally, the grid 41 is connected to the negative bus (—) through the back-contacts 91 and 92 of the four sensitive fault-detectors IOL, Z3A, Z3B and Z3C. If any one of these fault-detectors responds, the negative connection is broken, and the resistor R immediately brings the grid to the potential of the positive bus (+). If the ground-fault detector IOL responds, not only is the grid made positive, starting carrier-current transmission, but the phase-fault directionally responsive relay CSP is also rendered powerless thereafter to make the grid negative and stop the carrier-current transmission. If the ground-fault directionally responsive relay CSG responds, the grid is made negative, stopping the carrier-current transmission, regardless of the condition of any of the other responses. The rest of the Fig. 3 circuit is or may be the same as that shown in Fig. 2 and no further description is believed to be necessary.

25 While I have illustrated my invention in two forms of embodiment which are at present preferred by me, it is obvious that many changes in details of execution may be made without departing from some of the broader principles of my invention. I desire, therefore, that the appended claims shall be accorded the broadest construction consistent with their language and the prior art.

30 I claim as my invention:

1. Preferential relaying equipment for an alternating-current transmission-line, including a signal-current pilot-channel between the ends of a line-section to be protected, and further including, at each of said ends, a circuit-interrupter means and trip-circuit means for actuating said circuit-interrupter means, including two different kinds of fault-responsive relaying means, one of said responses being a preferential-fault 35 response, and the other being an other-fault response, each of said fault-responsive relaying means including both a fault-detector relaying means and a directional relaying means operative less rapidly than its corresponding fault-detector 40 relaying means, a signal-current receiver, and a

signal-current transmitter, characterized by said transmitter having a grid-controlled tube, and controlling means for normally supplying a blocking potential to said grid-circuit during normal operating conditions of said transmission line, 45 said controlling means including, in combination, a source of biasing potentials, an impedance-device, and four circuit-make-and-break means controlled by different ones of said four relaying means, including the following arrangement, in 50 combination; a first means, connected in said grid-circuit at a point close to the grid, for making sure that the grid has a blocking potential thereon whenever, and only whenever, said preferential-fault direction means responds, regardless of any other responses; a second means so connected in said grid-circuit as to make sure that the grid has a non-blocking potential thereon whenever, and only whenever, said preferential-fault detector means responds, and when, and 55 only when, said first means is non-responsive, regardless of any other-fault responses; a third means, connected in said grid-circuit in a manner different from said first means, and in such manner as to make sure that said grid has a blocking 60 potential thereon when, and only when, said first and second means are non-responsive and when, and only when, said other-fault directional means responds; and a fourth means, connected in said grid-circuit in a manner different from either 65 said first or second means, for making sure that said grid has a non-blocking potential thereon in response to a response of said other-fault detector means when, and only when, neither said first nor third means is operative to apply a blocking 70 potential to the grid.

2. The invention as defined in claim 1, characterized by a grid-circuit comprising four impedance-portions serially connected between the grid and the source of blocking potential, the first impedance-portion being closest to the grid, 75 said second means being operative to complete a circuit between the source of non-blocking potential and the junction between the first and second impedance-portions, said third means being operative to complete a circuit between the source of blocking potential and the junction between the second and third impedance-portions, and said fourth means being operative to complete a circuit between the source of non-blocking 80 potential and the junction between the third and fourth impedance-portions.

3. The invention as defined in claim 1, characterized by said impedance-device being connected between the grid and the source of non-blocking potential, and said second and fourth means being serially connected normally closed relay-contacts.

4. The invention as defined in claim 1, characterized by said impedance-device being connected between the grid and the source of non-blocking potential, said second and fourth means being serially connected normally closed relay-contacts, and said third means being a normally open relay-contact connected in shunt around 85 said fourth means.

5. The invention as defined in claim 1, characterized by each of said directional relaying means comprising a sensitive directional element and a fault-detector element, both responsive to the same kind of currents, and connections whereby both of said elements must respond before said directional relaying means will indicate a response, said fault-detector element being less sensitive than its associated fault-de- 90

tector relaying means which controls the transmitter grid-potential.

6. The invention as defined in claim 1, characterized by said transmission line being poly-phase, one kind of fault-responsive means being phase-fault responsive, the other kind being ground-fault responsive, the phase-fault directional relaying means comprising a plurality of pairs of single-phase elements connected in different phases, one of said elements of each pair being a sensitive directional element and the other being a fault-detector element, both responsive to phase-to-phase currents in the same delta phase, the ground-fault directional relaying means comprising a pair of elements, one being a sensitive ground-fault directional element and the other being a ground-fault detector element, and connections whereby both of the elements of some pair must respond before the corresponding directional relaying means will indicate a response, each fault-detector element being less sensitive than its associated fault-detector relaying means which controls the transmitter grid-potential.

7. Preferential relaying equipment for an alternating-current transmission-line, including a signal-current pilot-channel between the ends of a line-section to be protected, and further including, at each of said ends, a circuit-interrupter means and trip-circuit means for actuating said circuit-interrupter means, including two different kinds of fault-responsive relaying means, one of said responses being a preferential-fault response, and the other being an other-fault response, each of said fault-responsive relaying means including both a fault-detector relaying means and a directional relaying means operative less rapidly than its corresponding fault-detector relaying means, a signal-current receiver, and a signal-current transmitter, characterized by said transmitter having a grid-controlled tube, and controlling means for normally supplying a blocking potential to said grid-circuit during normal operating conditions of said transmission line, said controlling means including, in combination, a source of biasing potentials, an impedance-device, and a plurality of contact-means controlled by different ones of said four relaying means, including the following arrangement, in combination; first contact-means, connected in said grid-circuit at a point close to the grid, for making sure that the grid has a blocking potential thereon whenever, and only whenever, said preferential-fault directional means responds, regardless of any other responses; second contact-means so connected in said grid-circuit as to make sure that the grid has a non-blocking potential thereon whenever, and only whenever, either one of said detector-means responds, and when, and only when, said first contact-means is non-responsive; and third contact-means, connected in said grid-circuit in a manner different from said first contact-means, and in such manner as to make sure that said grid has a blocking potential thereon when, and only when, said first contact-means and said preferential-fault detector-means are both non-responsive and when, and only when, said other-fault directional means responds.

8. The invention as defined in claim 7, characterized by said impedance-device being connected between the grid and the source of non-blocking potential, and said second contact-means being normally closed contact-means.

9. The invention as defined in claim 7, charac-

terized by each of said directional relaying means comprising a sensitive directional element and a fault-detector element, both responsive to the same kind of currents, and connections whereby both of said elements must respond before said directional relaying means will indicate a response, said fault-detector element being less sensitive than its associated fault-detector relaying means which controls the polarity of said signal-current control-means.

10. The invention as defined in claim 7, characterized by said transmission line being poly-phase, one kind of fault-responsive means being phase-fault responsive, the other kind being ground-fault responsive, the phase-fault directional relaying means comprising a plurality of pairs of single-phase elements connected in different phases, one of said elements of each pair being a sensitive directional element and the other being a fault-detector element, both responsive to phase-to-phase currents in the same delta phase, the ground-fault directional relaying means comprising a pair of elements, one being a sensitive ground-fault directional element and the other being a ground-fault detector element, and connections whereby both of the elements of some pair must respond before the corresponding directional relaying means will indicate a response, each fault-detector element being less sensitive than its associated fault-detector relaying means which controls the polarity of said signal-current control-means.

11. Preferential relaying equipment for an alternating-current transmission-line, including a signal-current pilot-channel between the ends of a line-section to be protected, and further including, at each of said ends, a circuit-interrupter means and trip-circuit means for actuating said circuit-interrupter means, including two different kinds of fault-responsive relaying means, one of said responses being a preferential-fault response, and the other being an other-fault response, each of said fault-responsive relaying means including both a fault-detector relaying means and a directional relaying means operative less rapidly than its corresponding fault-detector relaying means, a signal current receiver, and signal-current control means comprising an impedance device, a source of potentials of a first polarity and a different second polarity, means for normally connecting said signal-current control-means to said first polarity during normal fault-free operating-conditions of the transmission line, first circuit-controlling means associated with said impedance device and source in a manner such as to assure that said signal-current control-means has said first polarity whenever, and only whenever, said preferential-fault directional means responds, regardless of any other responses; second circuit-controlling means associated with said impedance device and source in a manner such as to assure that said signal-current control-means has said second polarity whenever, and only whenever, said preferential-fault detector-means responds, and when, and only when, said first circuit-controlling means is non-responsive, regardless of any other fault responses; third circuit-controlling means associated with said impedance device and source in a manner such as to assure that said signal-current control-means has said first polarity when, and only when, said first and second circuit-controlling means are non-responsive and when, and only when, said other-fault direc-

- tional means responds; and fourth circuit-controlling means associated with said impedance device and source in a manner such as to assure that said signal-current control-means has said second polarity in response to a response of said other-fault detector-means when, and only when, neither said first nor third circuit-controlling means is effective to apply said first polarity to said signal-current control means.
12. The invention as defined in claim 11, characterized by a circuit comprising four impedance-5 portions serially connected between the signal-current control-means and the source of blocking potential, the first impedance-portion being closest to said signal-current control-means, said second circuit-controlling means being operative to complete a circuit between the second-polarity source and the junction between the first and second impedance-portions, said third circuit-controlling means being operative to complete a circuit between the first-polarity source and the junction between the second and third impedance-portions, and said fourth circuit-controlling means being operative to complete a circuit between the second-polarity source and the junction between the third and fourth impedance-portions.
13. The invention as defined in claim 11, characterized by said impedance-device being connected between said signal-current control-means and the second-polarity source, and said second and fourth circuit-controlling means being normally closed relay-contacts.
14. The invention as defined in claim 11, characterized by said impedance-device being connected between said signal-current control-means and the second-polarity source, said second and fourth circuit-controlling means being normally closed relay-contacts, and said third circuit-controlling means being a normally open relay-contact connected in shunt around said fourth circuit-controlling means.
15. The invention as defined in claim 11, characterized by each of said directional relaying means comprising a sensitive directional element and a fault-detector element, both responsive to the same kind of currents, and connections whereby both of said elements must respond before said directional relaying means will indicate a response, said fault-detector element being less sensitive than its associated fault-detector relaying means which controls the polarity of said signal-current control-means.
16. The invention as defined in claim 11, characterized by said transmission line being poly-phase, one kind of fault-responsive means being phase-fault responsive, the other kind being ground-fault responsive, the phase-fault direction relaying means comprising a plurality of 55 pairs of single-phase elements connected in different phases, one of said elements of each pair being a sensitive directional element and the other being a fault-detector element, both responsive to phase-to-phase currents in the same delta phase, the ground-fault directional relaying means comprising a pair of elements, one being a sensitive ground-fault directional element and the other being a ground-fault detector element, and connections whereby both of the elements of some pair must respond before the corresponding directional relaying means will indicate a response, each fault-detector element being less sensitive than its associated fault-detector relaying means which controls the polarity of said signal-current control means.
17. Preferential relaying equipment for an alternating-current transmission-line, including a signal-current pilot-channel between the ends of a line-section to be protected, and further including, at each of said ends, a circuit-interrupter 5 means and trip-circuit means for actuating said circuit-interrupter means, including two different kinds of fault-responsive relaying means, one of said responses being a preferential-fault response, and the other being an other-fault response, each of said fault-responsive relaying means including both a fault-detector relaying means and a directional relaying means operative less rapidly than its corresponding fault-detector relaying means, a signal-current receiver, and signal-current control-means comprising an impedance device, a source of potentials of a first polarity and a different second polarity, means for normally connecting said signal-current control-means to said first polarity during normal fault-free operating conditions of the transmission line, first circuit-controlling means associated with said impedance device and source in a manner such as to assure that said signal-current control-means has said first polarity whenever, and only whenever, 10 said preferential-fault directional means responds, regardless of any other responses; second circuit-controlling means associated with said impedance device and source in a manner such as to assure that said signal-current control-means has said second polarity whenever, and only whenever either one of said detector-means responds, and when, and only when said first circuit-controlling means is non-responsive; and third circuit-controlling means associated with said impedance device and source in a manner such as to assure that said signal-current control-means has said first polarity when, and only when, said second circuit-controlling means and said preferential-fault detector-means are both 15 non-responsive and when, and only when, said other-fault directional means responds.
18. The invention as defined in claim 17, characterized by said impedance device being connected between said signal-current control-means and the second-polarity source, and said second circuit-controlling means being normally closed contact-means.
19. The invention as defined in claim 17, characterized by each of said directional relay means comprising a sensitive directional element and a fault-detector element, both responsive to the same kind of currents, and connections whereby both of said elements must respond before said directional relaying means will indicate a response, said fault-detector element being less sensitive than its associated fault-detector relaying means which controls the polarity of said signal-current control-means.
20. The invention as defined in claim 17, characterized by said transmission line being poly-phase, one kind of fault-responsive means being phase-fault responsive, the other kind being ground-fault responsive, the phase-fault directional relaying means comprising a plurality of 60 pairs of single-phase elements connected in different phases, one of said elements of each pair being a sensitive directional element and the other being a fault-detector element, both responsive to phase-to-phase currents in the same delta phase, the ground-fault directional relaying means comprising a pair of elements, one being a sensitive ground-fault directional element and the other being a ground-fault detector element, and connections whereby both of the elements of 65 some pair must respond before the corresponding directional relaying means will indicate a response, each fault-detector element being less sensitive than its associated fault-detector relaying means which controls the polarity of said signal-current control-means.

some pair must respond before the corresponding directional relaying means will indicate a response, each fault-detector element being less sensitive than its associated fault-detector relaying means which controls the polarity of said signal-current control-means.

21. Relaying equipment for an alternating-current transmission-line, including a signal-current pilot-channel between the ends of a line-section to be protected, and further including, at each of said ends, a circuit-interrupter means and trip-circuit means for actuating said circuit-interrupter means, including a fault-detector relaying means and a directional relaying means both responsive to the same kinds of faults on the transmission-line, a normally non-transmitting signal-current transmitter, means responsive to a response of said fault-detector relaying means for initiating the operation of said signal-current transmitter, a signal-current receiver, and a receiver-relay having a trip-circuit contact, means for holding said receiver-relay in a non-tripping position during normal fault-free operating conditions of the transmission line, means responsive to a receipt of sufficient signal-current by said receiver for blocking movement of said receiver-relay to its tripping position, and means responsive to a response of said directional relaying means for nullifying the transmitter-controlling action of said fault-detector relaying means and for causing said receiver-relay to move to its tripping position in the absence of said blocking action, characterized by said directional relaying means comprising a sensitive directional element and a fault-detector element, and connections whereby both of said elements must respond before said directional relaying means will indicate a response, said fault-detector element being less sensitive than said fault-detector relaying means.

22. The invention as defined in claim 21, characterized by said transmission-line being polyphase, and said trip-circuit means comprising a plurality of pairs of phase-fault single-phase fault-detector relaying means and phase-fault single-phase directional relaying means, as defined, for the respective phases.

23. The invention as defined in claim 21, characterized by said transmission-line being polyphase, and said trip-circuit means comprising a plurality of pairs of phase-fault single-phase fault-detector relaying means and phase-fault single-phase directional relaying means, as defined, for the respective phases, the two elements of each phase-fault directional relaying means

being both responsive to the same kind of currents.

24. The invention as defined in claim 21, characterized by said transmission-line being polyphase, and said trip-circuit means comprising a plurality of pairs of phase-fault single-phase fault-detector relaying means and phase-fault single-phase directional relaying means, as defined, for the respective phases, and another set of ground-fault-detector relaying means and ground-fault directional relaying means, as defined, for ground-fault protection, said phase-fault and ground-fault relaying means providing, one a preferential-fault response, and the other an other-fault response, and means whereby, when said preferential-fault-detector relaying means is operative to cause the operation of said signal-current transmitter, said other-fault directional relaying means shall be inoperative to block said operation of said signal-current transmitter.

25. Relaying equipment for an alternating-current transmission-line, including a signal-current pilot-channel between the ends of a line-section to be protected, and further including, at each of said ends, a circuit-interrupter means and trip-circuit means for actuating said circuit-interrupter means, including a phase-fault-detector relaying means and a phase-fault directional relaying means responsive to line-to-line faults on the transmission-line, a normally non-transmitting signal-current transmitter, means responsive to a response of said fault-detector relaying means for initiating the operation of said signal-current transmitter, a signal-current receiver, and a receiver-relay having a trip-circuit contact, means for holding said receiver-relay in a non-tripping position during normal fault-free operating conditions of the transmission line, means responsive to a receipt of sufficient signal-current by said receiver for blocking movement of said receiver-relay to its tripping position, and means responsive to a response of said directional relaying means for nullifying the transmitter-controlling action of said fault-detector relaying means and for causing said receiver-relay to move to its tripping position in the absence of said blocking action, characterized by said directional relaying means comprising a sensitive directional element and a fault-detector element, and connections whereby both of said elements must respond before said directional relaying means will indicate a response.
